EUGENE KRAMER,

Inventor

By his Attorney Julian Mittal

UNITED STATES PATENT OFFICE.

EUGENE KRAMER, OF ASTORIA, NEW YORK.

DESIGN FOR A BOX.

Application filed December 15, 1926. Serial No. 20,055. Term of patent 3½ years.

To all whom it may concern:

Be it known that I, EUGENE KRAMER, a citizen of Hungary, residing at Astoria, in the county of Queens and State of New York, have invented a new, original, and ornamental Design for a Box, of which the following is a specification, reference being had to the accompanying drawing, forming a part thereof.

The figure is a perspective view of a box, showing my new design.

I claim:

The ornamental design for a box, as shown.
